CLAIM

The ornamental design for a telephone, as shown and described.

DESCRIPTION

FIG. 1 is a right side elevational view of a telephone showing my new design, the side opposite being a mirror image thereof;

FIGS. 2 and 3 are respectively bottom and top plan views thereof;

FIGS. 4 and 5 are respectively front and rear elevational views thereof; and

FIG. 6 is a front, bottom and left side perspective view thereof.
